LOAD BINDER

Votaw S. Durbin, Webster Groves, Mo.

Application April 17, 1948, Serial No. 21,669

4 Claims. (Cl. 254—78)

1

This invention relates to improvements in load binders, and considered broadly, relates to toggle-type tensioning devices such as may be employed in tightening a chain, cable or the like, for example, in securing of logs, pipes, poles and similar articles together as a unit load, and in place on vehicles for the purposes of preventing shifting of the load. Numerous other fields of usage of devices of this general order, are known in the art.

Although toggle type tensioning devices such as exemplified by load binders, have been in use for many years, there has long existed a common cause of their failure under conditions of extreme or abnormal loading. Assemblies of this type usually employ a handled lever, the shorter, actuated lever arm of which carries spaced pivots. Such an element operates, when locked, in interfitting relation to one element of a connected linkage, one of such elements, more usually the lever end, being formed of spaced furcations necessarily kept parallel so as to maintain the pivot axes in correct operative relation. The prevalent source of failure consists of spreading or divergence of the furcations, leading under extreme conditions, to a disconnection of the pivoted parts and failure of the binder as a load retaining agency, often with high likelihood of personal injury and perhaps loss of valuable property constituting the load. The present improvements accordingly have as a principal object, to obviate the noted spreading tendency of the furcations or jaws, and to enable safely raising the rated maximum pull to which devices of this kind may be subjected. The present invention is related in part to and embodies certain improvements over a copending application bearing Serial No. 744,808 filed April 30, 1947, now Patent No. 2,500,488, patented March 14, 1950, and entitled Load Binding Devices.

The invention has as a further important object a greatly improved construction of the furcate elements forming the mouth, particularly in the design and proportions thereof, so as greatly to enhance the resistance of its furcations to spreading tendencies or other deformation out of original register and parallelism. In the preferred example, this consists of a generally triangular form of each of the furcations, so as to provide for maximum width thereof in the region of one of the pivot axes.

Still another object of the present invention is attained in an improved combination of the generally triangular form of furcations defining the mouth of a lever or linkage element of a load

2

binder, with an improved, preferably integral bridge between the spaced furcations or jaws defining the mouth.

The foregoing and numerous other objects will more clearly appear from the following detailed description of a preferred embodiment of the invention, particularly when considered in connection with the accompanying drawing, in which:

- 10 Fig. 1 is a side elevation of a load binder embodying the present improvements, and showing the parts in an open position, prior to tensioning a chain or the like;
- 15 Fig. 2 is a view similar to Fig. 1, but showing the parts of the binder in locked or load-securing relation;
- 20 Fig. 3 is an enlarged transverse section through portions of the mouth and tongue of the assembly, and taken along line 3—3 of Fig. 2, and
- 25 Fig. 4 is an isometric view of the mouth end of the lever, with the handle broken away.
- Referring now by characters of reference to the drawing, certain of the major elements of the present structure, included for completeness and illustration of operation, are or may be of known construction, but it may be indicated for fullness of disclosure that a chain, certain links of which are indicated at C, will usually be employed to embrace with the aid of the binder, a load of poles, logs, pipe or the like. Obviously, also the device may be used with the chain, as for the lifting of loads or other general tensioning purposes where movement is required only through a relatively restricted range. A pair of chain-engaging hooks 10 and 11 are each shown as provided with adjacent links, these being indicated at 12 and 13 respectively, each of these links being permanently secured to and through the aperture of an eye bolt or swivel such as 14 engaging the link 12, and 15 engaging the link 13. The eye 15 is shown as pivotally connected in the manner of a swivel, through an apertured head portion 16 operating adjacent an enlargement 17, formed as a part of a tongue member generally indicated at 20. Similarly, the eye member 14 is connected for swivel movement through the bridge portion 21 of a clevis, and the latter generally indicated at 22.
- The actuating lever of the device includes a handle portion proper indicated at 23, which is preferably of I beam section, and which may be of any suitable length, and one end of which is connected as through a divergent portion 24, to a bifurcate mouth-forming portion generally indicated at 25. Assuming, as is preferred in the

present example, that the lever be formed as a single malleable casting, the furcate end 25 will constitute an integral extension of portions 23 and 24.

The tongue 20 has its end opposite the eye 15, pivotally connected as through a pin 26 at a substantial depth within the mouth formed by and between the jaws or furcations of portion 25. It will now clearly appear that the tongue 20 is arranged to extend and work between the furcations of the mouth 25, external pivot means being provided near the opposite extremities of the mouth furcations. In the present example, the outermost pivot may consist of integral projections or ears 30, which extend outwardly of the free end portions of the furcations sufficiently to extend through pivot openings therefor in the free ends of the arms of clevis 22.

In order to render more meaningful the structure characterizing the present improvements, later to be described, a brief reference is made at this point to operation. With the chain C brought around the load in snugly embracing relation thereto, and with the hooks 10 and 11 engaging the chain, the handle 23 is initially positioned as far to the right (Fig. 1) as possible, and the chain tensioned by movement of the handle to the left (Fig. 1) to bring it to a position such as shown by Fig. 2. The relative positions of the hook 11 in Figs. 1 and 2, will indicate the substantial tensioning effect incident to the aforesaid movement of the handle 23. Incident to such movement, it will have appeared that the elements 20, 25 and 22 serve as a toggle linkage; that the toggle thus constituted is first brought to a "centered" relation and thereafter brought to a slightly over-centered relation, as will best appear from Fig. 2, wherein the line of pull connects the eye elements 14 and 15, and lies somewhat above the pivot 26. Thus the tension through the device will tend to maintain the binder in locked or operative position, requiring a definite, intentional opposite movement of the handle to open the binder or bring it to released position.

As hereinbefore generally referred to, in case a furcate structure such as that of the mouth 25, is subjected to an abnormal loading in a general direction lengthwise thereof, there will result a tendency of the furcations to spread or diverge, greatly enlarging the open end of the mouth, and causing dislocation and disengagement of the outer pivots, this effect being most pronounced in the region of the axis of pivots 30, about which the mouth and clevis are relatively displaceable. After numerous experiments it has been found that a structural bridge between the furcations forming the mouth, will enable the device to resist substantially greater loading, often doubling the otherwise safe loading, without noticeably resulting in the spreading tendency above referred to. Such a structural bridge is, of itself, disclosed and claimed in the copending application above referred to. In the principal embodiment of the present structure the bridge proper is shown as a tunnel-like extension of the mouth proper and indicated at 25A, and which consists of an arch structure underlying but formed as an integral part of the furcations proper 33 and 34, which form therebetween the mouth 35, best appearing in Fig. 3.

Although experience has indicated that the maximum tension or loading which the device will successfully withstand without spreading of its jaws or furcations is very considerably en-

hanced by the integral bridge such as 25A, a still further substantial increase in safe rating of tension or load of the device is imparted by improvement of design of the furcations or jaws proper. Instead of the prevalent and more usual offset of the mouth from the handle of the actuating lever, as is sometimes referred to in the trade as a "dog-leg" design, the present design distinguished, with a greatly increased permissive load. Since each of the furcations is or may be identical with the other except of course relatively reversed in position, a description of one thereof will suffice for both. It will appear from the drawing that, proceeding from the handle proper toward the free end of the handle-mouth element as viewed in side elevation, the handle markedly diverges to form a portion in the region of the pivot 26, which is preferably of at least double the width of the handle proper. This widest portion may be considered as the base of a triangle generally defining the lateral shape of each of the furcations such as 33 and 34, and from which zone the jaws or furcations converge toward the free extremity of the actuated end of the lever element. It will appear clearly from the drawing that the mouth proper and the furcations are each of a generally triangular shape which is defined or bounded in part by the location of the pivot axes in the regions of two of the apices of each of the triangles.

It has been found by exhaustive experiments that it is very important to protect not only the outer mouth portion against spreading, as is effectively done by the bridge 25A, but also to guard against such deformation in the region of the inner pivot such as 26 which serves to attach the tongue 20 to the lever. In this latter region will be noticed the greatly augmented width of the furcations along the base of the triangular structure, this being along a line transverse to the axis of the handle and also transverse to the pivot axis identified with the pivot structure 26, the line of maximum width, indicated at 40 being the base of the quasi-triangular outline of jaw 33, as shown.

Further considerable rigidity and resistance to spread of the furcations is imparted by adding only a minimum of metal in the formation of the jaws, to present outwardly projecting flanges or flange formations such as shown at 41 along the margin opposite the bridge, a similar flange 42 on each jaw along the opposite margin in converging relation to the flange 41, and a pair of intermediate integral rib-like formations 43. Similarly it has been found that the bridge 25A is rendered desirably more rigid by a prominent flange or external rib 44 along its outermost margins, and a similar although if desired a smaller such rib 45 along its inner margin. These various added features have been proven, by careful and repeated experiments, to increase the safe permissive loading of the device by several thousand pounds over one in which the jaws or furcations are of conventional construction. The metal added in the general regions as described, is markedly more effective than the same amount of metal utilized merely in increasing the over all gauge or thickness of jaws of conventional construction. As heretofore indicated, the greatest resistance to deformation under extreme loading, is realized by utilizing both the bridge such as 25A or some counterpart thereof, and the generally triangular jaw structure. It is a preference for best results to avoid any of the usual reduction or relief along the edges in the regions

identified with the flange formation 41, but rather, to the full extent permitted by operating clearances, to extend these portions so that their margins are arched or convex as shown.

The proportions of the tongue, mouth and bridge are preferably such that, as the parts are moved into operative or locked position, the innermost margin of the tongue when slightly overcentered, abuts with the inner surface of the bridge 25A. From this it will appear that the bridge serves not only as a positive tie bar between the jaws of the mouth to prevent spreading thereof, but also serves in a positive manner to limit the movement of the tongue in a locking direction. An important, further feature resulting from the location and downward extension of the bridge structure 25A, is realized in the function of this portion as a downward projection or arm to serve as a rocker and bearing upon the top of the load. A comparison of the positions of bridge 25A in Figs. 1 and 2, will reveal that when the outermost edge of flange 44 is brought beyond a horizontal position, this margin of the bridge serves as an abutment, cam or rocker resulting in a slightly increased tension of the load tie, hence resistance to movement of handle 23. This resistance quickly disappears as the handle is brought slightly beyond a vertical position, in locking direction. The noted effect is markedly advantageous, in that it serves to prevent unintended unlocking or release of the binder, since the opposite, or clockwise movement of the handle (Figs. 1 and 2) would meet the same resistance in bringing the handle back over the range of its movement in which the bridge encounters the load therebeneath. The movement of the handle 23 to bring the parts into locking position is facilitated by rounding the center marginal portion of the bridge in the outer region of the mouth, as indicated at 46, this rounded region serving as a cam or rocker in the manner and with the advantages noted.

Although the tie bar or bridge structure indicated at 25A will, when formed on the jaws, markedly increase their resistance to spreading stresses, it should nevertheless be pointed out that this provision alone falls considerably short of the maximum attainment of resistance to spreading realized by the present improvements. To give but a single concrete example predicated on actual independent tests, malleable cast types of older conventional design will sometimes fail under tension loads of the order of 5,000-6,000 lbs., whereas those of comparable design and weight, in cast malleable type embodying the present improvements, have repeatedly withstood tests in accordance with independent determinations, of the order of 23,000-25,000 lbs. chain tension. The same proportion of increase in permissive tensile loading, prevails indifferent sizes of load binders. It may be noted that, as indicated by the foregoing test figures, the present improvements enable binders of malleable cast type to exceed the greatest possible loading of conventional drop forged designs, conservatively by 7,000 lbs. in sizes comparable to those subjected to the tests above described. It should further be noted that the present design enables, for the first time, malleable load binders to be produced, within acceptable weight range, carrying load ratings safely and substantially above those required by the various State laws and regulations governing apparatus of this type.

Although the invention has been described by making a particularized reference to selected

structure, the detail of description is to be understood solely in an instructive and not in any limiting sense, numerous variants being possible within the scope of the claims hereunto appended.

I claim as my invention:

1. In a load binder, an elongate lever including a handle and a furcate end forming a mouth between the furcations thereof, a tongue pivoted to the lever substantially inwardly of the mouth, pivot members projecting externally of the furcations near the outer end of the mouth, connections externally of the mouth, to said pivot members, and extensions of the furcations beyond the mouth proper, formed of spaced walls connected together and constituting a tension piece bridging the furcations in a zone substantially outwardly beyond the tongue pivot, said connected extensions bridging one side of the mouth over a substantial portion of the distance between said tongue pivot and the external pivot members.
2. In a load binder, a lever having a furcate end with a mouth between the furcations, a tongue pivoted to the lever at a distance inwardly of the mouth, pivot-forming members projecting externally of the furcations near their outer ends, a further connecting piece engaging said pivot-forming members, the lever, tongue and connecting piece constituting a toggle-type linkage, and a tunnel structure constituted as an extension of the normally lowermost margin of the mouth, and constituting a cross connection and tension bridge between the furcations of the lever, the inside extremity of said tunnel structure adapted to be abuttingly engaged by the tongue along a substantial part of one side margin of the tongue when the parts of the binder are in operative position, with the linkage elements brought slightly beyond a centered relation of said linkage.
3. In a load binder, a handle having spaced furcations of a generally triangular shape extended from one end of the handle, a tongue pivoted at a distance substantially inwardly of the free ends of said furcations, pivot elements projecting outwardly of the furcations near their free ends, the furcations being characterized by an extended portion of both furcations, such extension being of a substantially U-shaped transverse section and located in the general region of said outer pivots, the bridge of the U-shaped portion serving as a tension piece to resist spreading of the external pivots under extreme loads, and the bridge being further formed to provide thereon a rocker surface, engaging the load within the binder, and load connections from said external pivots.
4. In a load binder of a type including an operating lever provided with a mouth at one end, formed by spaced side walls, a tongue pivoted to the lever and operating across the mouth, a clevis connection externally of said side walls near their outmost ends, an arch structure formed integrally with said side walls, as a deep extension beyond the mouth proper along margins of the walls between the ends thereof, the arch structure being of increasing height or depth proceeding inwardly of the clevis connection, the tongue being of substantially rectilinear construction and under load, being received between said side walls and adapted to abut the internal surface of said arch structure, the side walls of the mouth, as well as the ends of the arch structure, being characterized by external

marginal flanges or ribs, and one end of said arch structure being rounded to provide externally thereon, a load-engaging rocker surface in a zone below the clevis connection when the binder is in a position of service.
